DESIGN FOR AN ENGINE EXHAUST STACK BOILER

Nathan C. Price, Hollywood, Calif.

Application November 9, 1940, Serial No. 96,452

Term of patent 7 years

To all whom it may concern:

Be it known that I, Nathan C. Price, a citizen of the United States, residing at Hollywood, in the county of Los Angeles and State of California, have invented a new, original, and ornamental Design for Engine Exhaust Stack Boilers, of which the following is a specification, reference being had to the accompanying drawing, forming part thereof.

Figure 1 is a side elevational view of an engine exhaust stack boiler, showing my new design;

Figure 2 is an end elevational view thereof;

Figure 3 is a perspective view thereof on a slightly enlarged scale.

I claim:

The ornamental design for an engine exhaust stack boiler, as shown.

NATHAN C. PRICE.
